UNITED STATES PATENT OFFICE

JOHN C. SHERMAN, OF GORHAM, MAINE

APPARATUS FOR EXCHANGING SAFETY-RAZOR BLADES

Application filed February 3, 1928. Serial No. 251,561.

This invention relates to apparatus whereby used safety razor blades may be removed from the razor and new blades inserted without either used or new blades being touched by the hands of the operator. The invention includes a novel package of blades which can be used in conjunction with a suitable support and a suitably constructed razor to carry out the purposes of the invention.

One of the safety razors now in wide use is open to the objection that the operation of changing blades is liable to be somewhat messy owing to the practical necessity of handling the end plate and blade as they are separated from the handle. There is also an ever-present danger of cuts in handling a keen two-edged blade. By this invention a rapid change of blades is facilitated without contact of the operator's fingers in the guard plate or blade.

In accomplishing the purposes of the invention, the razor construction is preferably so modified that when the cap is released from the handle portion of the razor, the blade itself will be releasably held with the handle portion, mechanism being provided by which the operator can release or pick up a blade without touching it with the fingers. In order to facilitate the operation of picking up new blades, I preferably provide them in a package in which the individual blades are separated by suitable spacers. I also provide a support adapted to hold my improved blade package so that the blades will be accessible, the support being also preferably provided with a device for releasably holding the cap of the razor when separated from the handle portion. A holder for the razor itself may also be mounted on the support.

For a more detailed disclosure of the invention, reference may be had to the following description and to the drawings, of which,

Figure 1 represents partly in section a safety razor of a well known type modified according to the invention to cooperate with blade-changing apparatus.

Figure 2 represents in perspective the end plate of the razor shown in Figure 1.

Figure 3 is a plan view of the handle portion of the safety razor in inverted position as shown in Figure 1, a blade being in position thereon.

Figure 4 is a plan view of a receptacle containing a blade package and a gripping device for the cap of the razor.

Figure 5 is a section on the line 5—5 of Figure 4.

Figure 6 is a section on the line 6—6 of Figure 4.

Figure 7 shows in elevation the end plate gripper engaging a cap, and the handle portion of the razor being removed therefrom.

Figure 8 is a perspective view showing the method of releasing a blade from the handle portion of the lever.

Figure 9 shows in elevation a portion of a blade package with the handle portion of a razor approaching to engage the topmost blade.

Figure 10 is a view partly in section of a modified form of safety razor.

Figure 11 is a detail on a larger scale of a portion of the razor shown in Figure 10.

Figure 12 is a perspective view of the same.

Figure 13 is a perspective view of the spacer element for the blade package.

Figure 14 is a perspective view of a complete package of blades.

Figure 15 is an elevation, partly broken away, illustrating the manner of mounting a package of blades on the blade-holding portion of the supporting stand.

Figure 16 shows in perspective a modified form of gripping device for the cap of the razor.

Figure 17 is a perspective view of a supporting stand for a complete outfit of razor, end plate gripper, and blade package.

Referring to the drawings in detail, 1 indicates the cap of a razor of well known type, the construction of which is modified according to the present invention. The cap as usual is provided with a pair of studs 2 by which it is kept in alignment when assembled with the other parts of the razor. Between the studs 2 is a threaded shank 3 for threaded engagement with a draw member 7 by which the cap 1 may be drawn toward the guard

plate 4 of the razor. When the razor is assembled complete, a blade is customarily between the cap 1 and the guard plate 4, the cap pressing the blade against the guard plate.

5 In order to retain the blade against the handle plate after the removal of the cap, a pair of gripping fingers 5 may be provided having catches 6 at the ends thereof adapted to enter a perforation of a blade and to hook on to the sides of the perforation. By pressing the fingers 5 toward each other, the catches 6 may be disengaged from the blade and the latter allowed to fall clear of the handle plate 4. In order to permit the catches 6 to move 10 toward each other far enough to clear the sides of the perforation in the blade, the shank 3 may be laterally slotted at 5^a, these slots serving to receive the end portions of the grip fingers. Suitable springs may be provided to press the fingers 5 outward. The 15 guard plate 4 may as usual be made integral with the handle 8 of the razor, the latter being hollow to receive the draw member 7 by which the cap 1 is drawn toward the handle plate 4 to grip a blade 9 therebetween. Instead of the grip fingers 5 as shown in Figure 1, suitable spring catches 5' may be mounted at the ends of the guard plate 4, these fingers 5' being provided with catches 6' adapted to engage over the ends of a blade 9 and to hold the blade against the guard plate 4 until released by manual operation of the fingers 5'. It will be noted that in either construction, the cap 1 projects out beyond the ends 20 of the blade 9 so that the ends of the cap 1 may be gripped by means which will not engage the blade. In order to facilitate the picking up of a blade by the handle member, it is preferred to space the blades apart so 25 that the catches 6 or 6' may readily engage the under face of a blade to be lifted. To this end, spacers 10 may be provided which may comprise a simple piece of cardboard or the like between each pair of blades as shown 30 in Figure 4, these spacers being preferably notched on their edges so as to be held in place between the blades. A more elaborate form of spacer may be provided as shown in Figure 13, this spacer being preferably of 35 the same general shape as the blade but of larger area, the spacer being recessed laterally on one or both of its faces so as to receive a blade within the recess in such a way that the blade will lie below the upper surface 40 level of the spacer. Along the side edges of each recess, the recess is preferably made slightly tapered so that the cutting edge of a blade received therein will not touch the bottom of the recess. The margins of the 45 spacers surrounding the recesses, being thicker than the rest of the spacers, will rest against each other when assembled in a package as shown in Figure 14 and will thus form a protective enclosure for each of the cutting 50 edges of the blades. In order to keep the 55 blades centered in their recesses so that the cutting edges will not touch the side walls thereof, slots 10" may be cut to extend in from the ends of each spacer, the inner ends of these slots preferably registering with 60 perforations 12 in the blades so that centering members 15 may be passed through the perforations and slots to hold the parts of the blade package together in properly centered relation. In order to facilitate the 65 removal of a spacer from the package after a blade has been removed therefrom, a handle piece 10' is extended outwardly from a corner thereof. In assembling spacers in a 70 package, these handles may be staggered as shown in Figures 14 and 17 so as to facilitate the grasping of one of them without interference by other handles in the package. When the blade package is placed on a stand for use, the centering tubes or pins 15 may be 75 replaced by fixed dowel pins 11 which may be mounted so as to project from a suitable support stand 13 or 13'. In order to facilitate the transfer of a package of blades and spacers from the centering means 15 to the 80 dowel pins 11, the latter may be shaped at their upper ends with a shoulder and a reduced portion 11'. The centering members 15 may preferably be in the form of tubes, the ends of which are of a size to fit over the 85 reduced portion 11' of the dowel pins 11 and to engage against the shoulders on these pins as shown in Figure 15. It is obvious from this figure that the blades and spacers may thus be easily transferred from the tubes 15 to the dowel pins 11. The supporting stand or block 13 may, as shown in Figure 5, be mounted in the bottom of a suitable receptacle of any desired material which may be provided with a cover to protect the apparatus from moisture and dust. Figure 17 shows a modified form of supporting stand 13' which may be provided with a cover member (not shown) to engage over the apparatus illustrated in the figure and to rest on a shoulder 13" near the bottom of the supporting block. In addition to dowel pins 11 for holding packages of blades, the supporting stands may also be provided with a resilient 90 gripping means 14 or 14' for releasably holding the cap 1 of the razor. The gripping means may as shown in Figures 4 and 6 comprise a pair of simple spring members suitably spaced to clamp lightly the cap which is thrust down between them against the base block 13, or as shown in Figures 16 and 17, the gripping means may comprise a base plate having the ends thereof turned out and notches to receive and hold a cap thrust between them. The gripper is preferably made of a metal having sufficient resilience to permit the end portions to spring apart when the cap is inserted or removed. The gripper and the blade holder are preferably arranged 95 as shown so that the long edge of the blades 100

and of the cap is transverse with respect to the supporting block. This parallel relation facilitates the manipulation of the razor in changing the blades since the razor may be transferred from the gripper to the blade package and back again to the gripper without being turned.

Also mounted on the supporting stand may be a resilient holder 17 adapted to grip the handle of a razor to hold the razor in place on the stand. This may comprise a simple spring clip having a pair of upwardly extending arms suitably spaced to receive the handle of the razor and to clamp it lightly.

In using the apparatus to exchange a used blade for a new blade, the razor is preferably thrust downwardly into the cap gripper 14 or 14' until the cap is engaged by the gripper. The draw member 7 is thereupon actuated to release the cap whereupon as shown in Figure 7, the handle portion and draw member of the razor may be lifted from the cap carrying the blade 9 therewith. The razor may then be held over a suitable receptacle for used blades and the fingers 5 pressed as shown in Figure 8, releasing the used blade 9 which is allowed to fall into the used blade receptacle. The handle member is thereupon placed on the uppermost blade of the blade package as shown in Figure 9, the spacing member thereon having previously been removed. The new blade is thereupon caught by the fingers 6 or 6' and lifted thereby with the handle of the razor. These members are then placed upon the cap 1 which meanwhile has been held by the gripper 14 or 14', and the draw member 7 is operated to draw the cap up as tightly as desired against the blade 9. The reassembled razor with a new blade therein may then be pulled from the gripper 14 or 14' and is ready for use, the blade having been changed without the fingers of the operator coming in contact therewith or with the cap.

Having thus described certain embodiments of my invention, it should be evident to those skilled in the art that various changes and modifications might be made therein without departing from its spirit or scope as defined by the appended claims.

I claim:—

1. Apparatus for facilitating change of blades in a safety razor, comprising a supporting stand, a package of safety razor blades having spacing elements between successive blades, means on said stand for holding said blades in place, and means on said stand for releasably holding the cap of a safety razor in parallel relation to said blades.

2. Apparatus for facilitating change of blades in a safety razor, comprising a supporting stand, a pair of parallel dowel pins projecting therefrom, said pins being spaced to receive perforated razor blades thereon,

and resilient means on said stand for releasably holding the cap of a safety razor in parallel relation to said blades.

3. Apparatus of the class described, comprising a supporting stand, a pair of parallel dowel pins projecting therefrom, said pins being spaced to receive perforated razor blades thereon, resilient means on said stand for releasably holding the cap of a safety razor, and other resilient means on said stand for releasably gripping the handle of a safety razor.

4. Apparatus of the class described, comprising a supporting stand, a safety razor having a perforated guard plate and a cap with pins adapted to enter the perforations of said guard plate, means on said razor for releasably holding a blade against the guard plate when the cap is released therefrom, means carried by said stand for releasably holding said cap, a package of blades for said razor having perforations adapted to register with the perforations in said guard plate, said package comprising a spacing element between each pair of successive blades, a pair of dowel pins mounted on said stand and spaced to enter the perforations in said blades and in said guard plate, and a resilient holder carried by said stand for releasably gripping said razor.

In testimony whereof I have affixed my signature.

JOHN C. SHERMAN.
